SWITCH ACTUATING DEVICE

Carl Herman Millerwise, Trumbull, Conn., assignor to American Radiator & Standard Sanitary Corporation, New York, N.Y., a corporation of Delaware

Application May 15, 1958, Serial No. 735,527

7 Claims. (Cl. 200—172)

The present invention relates to a switch actuating device. More particularly, this invention relates to an actuator structure for a plunger-operated switch having a housing with a surface through which a plunger projects and side surfaces extending from the plunger surface.

It is an object of this invention to provide a novel switch actuating device for a plunger operated switch.

It is another object of the invention to provide such a switch actuating device having "snap-on" bracket means for clamping engagement with the switch housing to provide a unit which may be easily mounted on a switch without the use of screws or other additional fastening means.

A further object of the invention is the provision of a switch actuating device which may be mounted on installed switches without removing the switch mounting means or otherwise disassembling the switch.

Another object is to provide a switch actuator having a resilient arm to actuate the switch plunger whereby the switch may be used for automatic intermittent switching operations such, for example, as limit switch applications.

A still further object of this invention is the provision of a switch actuating device which may be produced as a one-piece unit.

Another object is the provision of a switch actuating device which may be produced as a relatively low cost item as a result of its simplified construction.

Other objects of this invention will appear in the following description and appended claims, reference being had to the accompanying drawings forming a part of this specification wherein like reference characters designate corresponding parts in the several views.

In the drawings:

Fig. 1 is a side elevational view of a switch actuating device constructed according to the present invention.

Fig. 2 is a top plan view of the switch actuating device of Fig. 1 installed on a plunger type switch.

Fig. 3 is a side elevational view of the switch actuating device of Fig. 1 installed on a plunger type switch having recess mounting means for engagement with projections on the legs of the actuating device.

Fig. 4 is a segmental view of one end of the switch actuating device showing a second embodiment of the switch housing provided with projecting mounting means for engagement with projections on the legs of the actuating device.

Fig. 5 is an end elevational view of the Fig. 1 embodiment.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

It is contemplated by this invention to provide a switch

2

actuating device 10 having a mounting bracket 18 which may be snapped onto a switch 12, as may be best seen in Figs. 2 and 3, without the use of screws or other fastening means. The mounting bracket 18 carries the "switch actuating" portion of the device 10 which comprises a resilient arm 14 which extends over the switch plunger element 16 and, in its normal at-rest position, is spaced therefrom. The arm 14 is deflectable downwardly in the arrow 11 direction toward the bracket 18 to depress the plunger 16 which operates the switch 12 to an open or closed condition. The arm 14, being resilient, will always return to its normal at-rest position when the deflecting force is removed. The switch actuating device 10 as thus constructed may be used for a variety of switching operations.

As may be seen in Figs. 2 and 3, the switch 12 comprises a switch housing 28 having a generally oblong construction. The housing 28 has an upper surface 32 through which the switch plunger element 16 projects. The housing 28 is also provided with side surfaces 24, 26 extending downwardly from the upper surface 32. While a generally oblong structure has been shown for the switch housing 28, it will be obvious to one skilled in the art that the present invention is capable of being adapted to other housing shapes which may have, for instance, curved or angular surfaces. The switch 12 as shown for purposes of illustration is an electrical switch having switch terminals 50, 52 and 54, however, within the scope of the present invention it is only necessary that the switch 12 be of the plunger operated type. A plunger-operated switch is similar to the conventional "on-off" switch and may have any desired internal switch construction. The switch may be either normally open or normally closed and is equipped with a push button type of plunger 16 for actuating the switch to the non-normal "closed" or "open" position as the case may be. The plunger 16 is urged to its normal position by resilient means which may be, for example, a spring. A plunger-operated switch of the type contemplated is shown and described in U.S. Patent No. 2,669,618, issued to Bradley.

Referring to Figs. 1 and 2, the switch actuating device 10 comprises a generally U-shaped mounting bracket portion 18 having a pair of inwardly sprung legs 20, 22 adapted to clampingly engage the side surfaces 24, 26 of the switch housing 28. The legs 20, 22 are interconnected by means of an elongated web member 30 which extends across the upper surface 32 of the switch housing 28. The central portion of the web 30 is cut-away to form the elongated resilient actuating arm 14. The arm 14 has one of its ends 36 attached to the bracket 18 adjacent the leg 20 and has its opposite end 38 free, thus forming a movable spring leaf lever. The arm 14 is offset from the web 30, and consequently spaced from the plunger 16 which extends through the central open portion of the web 30, by means of an upwardly extending portion 34. The arm 14 as shown in Figs. 1 and 3, extends outwardly from the offsetting portion 34 and may be directed upwardly at a slight angle to the web 30 to provide additional spacing from the plunger 16.

As previously mentioned, the legs 20, 22 are sprung inwardly as shown in Fig. 1 to provide a clamping engagement with the side walls 24, 26 of the switch housing 28. The legs 20, 22 may additionally be provided with resilient flat projections 40, 42 to engage recesses 44, 46 formed in the side walls 24, 26. The projections 40, 42 may be formed from the material of the legs 20, 22 as shown in Fig. 5 by a method such, for example, as lancing. The provision of recesses, 44, 46 is a preferred method for engaging the projections 40, 42 since it provides a positive locking arrangement and permits legs 20, 22 to be flush with the side surfaces 24, 26. However, a second embodiment as shown in Fig. 4 is also

useful in some instances. In the Fig. 4 embodiment, projections 48 are provided on the surfaces 24, 26 for engagement with the upper end of the actuator leg projections 40, 42. Both the Figs. 3 and 4 arrangements permit the switch actuating device 10 to be securely mounted on the switch 12 by simply forcing the actuator legs down the sides 24, 26 until the projections 40, 42 snap into engagement with the recesses 44, 46 or the projections 48 as the case may be. It will be noted that due to the locking engagement of the projections 40, 42 to prevent vertical movement and of the switch plunger element 16 which projects through the web 30 to prevent sidewise movement, the actuator 10 cannot be accidentally removed from the switch 12. Before the actuator 10 can be removed, the projections 40, 42 must be bent outwardly, away from the walls 24, 26, to disengage them from the recesses 44, 46 or the projections 48. This will free the actuator 10 for upward movement and it may be thus conveniently removed from the switch 12, but only when desired.

The switch actuating device 10 is preferably fabricated from a single flat strip of resilient material such as spring steel to the end that the legs 20, 22, projections 40, 42 and the arm 14 will not be subject to permanent deformation due to the forces encountered during use. Resiliency is particularly important in reference to the arm 14 which in operation is subject to repeated flexing and must return to its open position after the closing force is removed.

In some applications, as when the switch 12 is to be used as a limit switch, it may be desirable to mount roller elements in the arm 14 to reduce the friction between the arm 14 and the follower element which is usually provided to slide over and deflect such limit switch actuating arms. It may also be desirable in some instances to hingedly mount the arm 14 to the bracket 18 rather than to form the arm 14 integrally therewith as a spring leaf actuating arm as shown in Fig. 1. The arm 14 might be hingedly mounted, for instance, when it is desired to have it remain in either the opened or closed position without the continued application of an external force.

Having thus described my invention, I claim:

1. An actuator structure for a plunger operated switch having a housing with a surface through which a plunger projects; said actuator structure comprising wall means; detent means on said wall means for clamping engagement with the switch housing and actuator means movably carried by the wall means for actuating the switch plunger.

2. A switch actuating device for use with a plunger operated switch having a housing provided with a surface through which the plunger projects and side surfaces extending adjacent the plunger surface; said actuating device comprising a mounting bracket portion having a web portion; a pair of legs depending from opposite ends of the web portion; said legs having detent means adapted to clampingly engage said switch housing side surfaces; and an elongated arm having one of its ends attached to the bracket and having its opposite end free; said arm adapted to extend over the plunger and adapted to be normally spaced therefrom whereby it is adapted to be swung into pressure engagement with the plunger when moved toward the switch housing.

3. A switch actuating device for use with a plunger operated switch having a surface through which the plunger projects and side surfaces extending from the plunger surface; said actuator comprising a generally U-shaped mounting bracket portion having a pair of inwardly sprung legs; detent means on said legs adapted to engage said side surfaces; the legs being interconnected by means of an elongated member adapted to extend across the plunger surface; and an elongated resilient arm having one of its ends attached to the bracket adjacent one leg and having its opposite end free; said arm ex-

tending over the plunger and normally spaced therefrom whereby it is adapted to be swung into pressure engagement with the plunger when moved toward the elongated interconnecting bracket member.

4. A switch actuating device for use with a plunger operated switch having a surface through which the plunger projects, side surfaces extending from the plunger surface, and a recess formed in each of the side surfaces; said actuating device comprising a generally U-shaped mounting bracket portion having a web portion adapted to extend across the plunger surface; a pair of resilient legs depending from opposite ends of the web portion sprung inwardly towards one another; an inwardly extending resilient projection on the inner surface of each of the legs; said legs adapted to clampingly engage said switch housing sides with each of the inwardly extending projections lockingly engaging the recess provided in each of said side surfaces; and an elongated resilient arm having one of its ends attached to the bracket and having its opposite end free; said arm adapted to extend over the plunger and adapted to be normally spaced therefrom whereby it is adapted to be swung into pressure engagement with the plunger when moved toward the switch.

5. A switch actuating device for use with a plunger operated switch having a surface through which the plunger projects, side surfaces extending from the plunger surface, and a projection formed on each of the side surfaces; said actuating device comprising a generally U-shaped mounting bracket portion having a web portion adapted to extend across the plunger surface; a pair of resilient legs depending from opposite ends of the web portion sprung inwardly towards one another; an inwardly extending resilient projection on the inner surface of each of the legs; said legs adapted to clampingly engage said switch housing sides with each of the inwardly extending leg projections abutting against the lower portion of the projection provided on each of said side surfaces in locking engagement therewith; and an elongated resilient arm having one of its ends attached to the bracket and having its opposite end free; said arm adapted to extend over the plunger and adapted to be normally spaced therefrom whereby it is adapted to be swung into pressure engagement with the plunger when moved toward the switch.

6. A switch actuating device for use with a plunger operated switch having a surface through which the plunger projects, side surfaces extending from the plunger surface, and a recess formed in each of the side surfaces; said actuating device comprising a generally U-shaped mounting bracket portion having a web portion adapted to extend across the plunger surface; a pair of resilient flat legs depending from opposite ends of the web portion sprung inwardly towards one another; an inwardly and upwardly extending flat resilient projection on the inner surface of each of the legs; said legs adapted to clampingly engage said switch housing sides with each of the inwardly extending projections lockingly engaging the recess provided in each of said side surfaces; and an elongated resilient arm having one of its ends attached to the bracket and having its opposite end free; said arm adapted to extend over the plunger and adapted to be normally spaced therefrom whereby it is adapted to be swung into pressure engagement with the plunger when moved toward the switch.

7. A switch actuating device for use with a plunger operated switch having a surface through which the plunger projects, side surfaces extending from the plunger surface, and a recess formed in each of the side surfaces; said actuating device comprising a generally U-shaped mounting bracket portion having a web formed with an elongated central opening adapted to extend across the plunger surface with the switch plunger extending through the web opening; a pair of resilient flat legs depending from opposite ends of the web portion sprung inwardly towards one another; an inwardly and upwardly

extending flat resilient projection on the inner surface of each of the legs; said legs adapted to clampingly engage said switch housing sides with each of the inwardly extending projections lockingly engaging the recess provided in each of said side surfaces; and an elongated flat resilient arm having one of its ends attached to the bracket adjacent one leg and having its opposite end free; said arm adapted to extend over the plunger and adapted to be normally spaced therefrom whereby it is adapted to be swung into pressure engagement with the 10 plunger when moved toward the switch.
